UNITED STATES PATENT OFFICE

ANTHONY KREBS, OF ROSELLE PARK, NEW JERSEY

CLOTHESPIN HOLDER

Application filed June 9, 1931. Serial No. 543,184.

This invention relates to clothes pin holders and has for one of its objects the provision of such a holder adapted to be attached to the body of a person.

5 Another object of the invention is the provision of a clothes pin holder adapted to hold clothes pins at a short distance away from the clothes of the person to which the holder is attached.

10 A further object is the provision of a clothes pin holder in which the clothes pins are necessarily placed with the heads in corresponding position so that the various pins will not have to be variously manipulated after being withdrawn from the holder as is necessary with pins held in a bag, the pins in the holder of my invention all being held in similar position.

20 Other objects of the invention will be apparent from a reading of the following specification.

The invention will be fully and comprehensively understood from a consideration of the following detailed description when read in connection with the accompanying drawing which forms part of the application, with the understanding, however, that the improvement is capable of extended application and is not confined to the exact showing of the drawing nor to the precise construction described and, therefore, such changes and modifications may be made therefrom as do not affect the spirit of the invention nor exceed the scope thereof as expressed in the appended claims.

35 In the drawing:

Fig. 1 is a perspective view showing a lady having attached to her person a clothes pin holder of my invention and in the act of hanging clothes.

40 Fig. 2 is a front view of the clothes pin holder; and

Fig. 3 is a side view of the holder showing several clothes pins held thereby.

45 Referring to the drawing for a more detailed description thereof, the clothes pin holder of my invention is preferably, although not necessarily, made from a single piece of fairly stout wire 5. The wire, intermediate its end portions, is bent alter-

nately in opposite directions to form a plurality of channels 6 adapted to receive the niches 7 of clothes pins 8 having heads 9. The channels 6 are narrower than the heads 9 of the clothes pins. The lower ends of the channels 6 are closed by the looped portions 10 of the wire and said channels are constricted at their upper or pin receiving ends 11 by means of the loops 12. The constriction of the channels, as will readily be appreciated, serves to retain the pins in the holder when the latter is not worn by a person and is, as may happen, in an inverted or upside down position.

55 The channel forming portion of the wire, as shown in Fig. 3, extends forwardly from extensions 15 and preferably at an acute angle thereto for the purpose of holding the clothes pins away from the body of the person carrying the holder. Beyond the extensions 15 end portions 16 of the wire are looped to form eyelets 17. A strap 18 is secured to one of said eyelets and carries a fastening element 19 adapted to be detachably connected to the other eyelet, said strap 60 adapted to go around a person's body as shown in Fig. 1.

65 What is claimed as new is:

1. A clothes pin holder comprising a strip bent alternately in opposite directions to form 70 channels adapted to receive the necks of the usual clothes pins, said channels being narrower than the heads of the pins.

2. A clothes pin holder comprising a strip bent alternately in opposite directions to form 75 channels adapted to receive the necks of the usual clothes pins, said channels being narrower than the heads of the pins, the end portions of the strip being bent to form eyelets.

80 3. A clothes pin holder comprising a strip bent alternately in opposite directions to form channels adapted to receive the necks of the usual clothes pins, said channels being narrower than the heads of the pins, the end portions of the strip being bent to form eyelets and fastening means secured to the eyelets 85 and adapted to go around a person's body.

90 4. A clothes pin holder comprising a strip bent alternately in opposite directions to form 95 channels adapted to receive the necks of the usual clothes pins, said channels being narrower than the heads of the pins, the end portions of the strip being bent to form eyelets and fastening means secured to the eyelets and adapted to go around a person's body.

100 5. A clothes pin holder comprising a strip bent alternately in opposite directions to form

channels adapted to receive the necks of the usual clothes pins, said channels being narrower than the heads of the pins, the strip being bent to constrict the channels at their pin-receiving ends.

5. A clothes pin holder comprising a strip bent alternately in opposite directions to form channels adapted to receive the necks of the usual clothes pins, said channels being narrower than the heads of the pins, said strip having extensions and the channel-forming portion of the strip extending forwardly from the extensions.

10. A clothes pin holder comprising a strip bent alternately in opposite directions to form channels adapted to receive the necks of the usual clothes pins, said channels being narrower than the heads of the pins, said strip having extensions and the channel-forming portion of the strip extending forwardly from the extensions at an acute angle.

20. In testimony whereof I hereby affix my signature.

ANTHONY KREBS.
